UNITED STATES PATENT OFFICE.

ZACHRY T. FURBISH, OF PHILADELPHIA, PENNSYLVANIA, ASSIGNOR TO NORTH BROTHERS MANUFACTURING COMPANY, OF PHILADELPHIA, PENNSYLVANIA, A CORPORATION OF PENNSYLVANIA.

MAGAZINE SPRING-DRILL.

SPECIFICATION forming part of Letters Patent No. 685,678, dated October 29, 1901.

Application filed February 28, 1901. Serial No. 49,269. (No model.)

To all whom it may concern:

Be it known that I, ZACHRY T. FURBISH, a citizen of the United States, residing in Philadelphia, Pennsylvania, have invented certain 5 Improvements in Magazine Spring-Drills, of which the following is a specification.

The object of my invention is to so construct a spring-drill that the drill-bits can be carried in the handle of the tool. This object I attain in the following manner, reference being had to the accompanying drawings, in which—

Figure 1 is a side view of my improved magazine spring-drill. Fig. 2 is a longitudinal sectional view showing the magazine closed. Fig. 3 is a view similar to Fig. 2, showing the magazine open. Fig. 4 is a plan view on the line 4 4, Fig. 2; and Figs. 5 and 6 are views of details of my invention.

20 A is the cap of the handle, to which is attached the spindle B, having a spiral groove b, in which travels a nut c on the tubular stem C. Between the end of this spindle B and a plug e is a spring E, which tends to 25 keep the tubular stem normally extended, as shown in the drawings. The stem C slides within a casing D, screw-threaded at its upper end and arranged to screw into the cap A, so that the cap, casing, and stem are all 30 secured together.

At the lower end of the tubular stem C is 35 a chuck F, secured to the sleeve by a screw or pin c'. This chuck may be constructed in any suitable manner to hold a drill-bit rigidly to the spindle.

Arranged to slide on the casing D is a casing G, and this casing is reduced at its lower end, forming a neck g, which snugly fits the casing D, and this neck is screw-threaded.

40 H is a screw-threaded collar arranged to screw on the neck g of the casing G, and within this collar is a split spring-ring h. (Shown in Fig. 5.) The ring is arranged to fit in a groove d in the casing D, so as to retain the casing G in its closed position. By 45 simply unscrewing the collar H the ring will be released and the casing G can be moved down upon a casing D, so as to expose the drill-bits within the pockets i between the 50 casings G and D.

A ribbed frame I, made in the present instance of sheet metal, is shaped to form the pockets i, as illustrated in Figs. 4 and 6, and it is bent to fit snugly the casing G and around the collar H.

55

Supporting the drills is a platform J, having a tubular stem j, fitting the casing D, and between the platform and the reduced portion of the casing G is a spring J', which tends to project the ends of the drill-spindles beyond the casing G when the said casing is lowered, as in Fig. 3. In closing the casing to the position shown in Fig. 2 the spring J' is compressed, so that on releasing the casing by unscrewing the collar H the 60 spring J' will force the casing G down to expose the drill-bits.

In order to prevent the handle turning when in its closed position, I notch the casing G at g' and make a projection a on the cap A.

70

The cap A in the present instance is made in two pieces, a' being the cap proper, having a screw-threaded portion which is screwed onto the portion a², and the pins a extend into the portion a², as shown in Fig. 2. The 75 upper end of the spindle is screwed into the portion a² and has a shoulder, as shown, and there is a loose washer a³ between this shoulder and the portion a² of the cap.

In the present instance the spindle B is 80 hung within the stem from a pin b', mounted in the cap A, and there is sufficient play to allow the spindle to accommodate itself to the nut c on the stem C.

The projection of the spindle is limited by 85 a head b² on the spindle B, and the nut c is held in place by a screw-plug c², screwed into the end of the hollow spindle.

By the construction shown it will be seen that I am enabled to make a very simple and 90 convenient spring-drill, in which the main spring and the rod with a spiral groove therein is mounted within a casing, while the drill-bits are mounted in a second casing arranged to slide upon the first casing and to be held 95 thereto and to a cap-piece by a suitable clutch—in the present instance a split ring and screw-sleeve—and the drill-bits are projected from the upper end of the casing by a suitable spring, so that the entire set of drills 100

can be seen and the one desired selected. When the casing is closed, the tool is perfectly rigid and can be used as an ordinary spring-drill.

5 I claim as my invention—

1. The combination in a magazine for drills, &c., of a central casing or support, a cap thereon, a magazine-casing arranged to slide on the central casing, and means for securing 10 the magazine-casing to the central casing, substantially as described.
2. The combination in a spring-drill, of a casing, spring-drill mechanism within the casing, a second casing arranged to slide upon 15 the first casing and carrying the magazine for the drill-bits, an overhanging cap on the first-mentioned casing, and means for holding the magazine to the cap, substantially as described.
- 20 3. The combination in a magazine spring-drill, of the casing, spring-drill mechanism within the casing, a magazine-casing arranged to slide upon the first-mentioned casing, means for securing the magazine-casing to 25 the fixed casing, and a spring-platform arranged to project the drill-bits when the magazine is detached from the cap, substantially as described.
4. The combination of a casing, spring-drill 30 mechanism within the casing, an overhanging cap secured to the end of the casing, a magazine-casing arranged to slide on the fixed casing, a screw-sleeve arranged to screw onto the end of the magazine-casing, a split ring 35 mounted between the said sleeve and the casing and acting as a clutch to secure the magazine-casing to the fixed casing, said magazine-casing arranged to hold a series of drill-bits, substantially as described.
- 40 5. The combination of a spring-drill, a tu-

bular casing, a tubular stem arranged to slide in said casing, a fixed spindle secured to the said casing and having a spiral groove therein, a nut engaging with said spirally-grooved spindle and secured to the tubular stem, and 45 a spring mounted within the said stem, substantially as described.

6. The combination in a spring-drill, of a tubular casing, a tubular stem arranged to slide in said casing, a fixed spindle secured 50 to the said casing and having a spiral groove therein, a nut engaging with said spirally-grooved spindle and secured to the tubular stem, a spring mounted within the said stem, with a magazine-casing mounted on the outside of the fixed casing, and means for securing the magazine-casing to the fixed casing, the cap of the fixed casing forming the cap of the magazine, substantially as described. 55

7. The combination in a spring-drill, of a 60 tubular casing, a spirally-grooved spindle hung loosely within the casing, a hollow stem arranged to carry a tool, a nut on said stem engaging the spindle, and a spring for projecting the stem, substantially as described. 65

8. The combination in a spring-drill, of a tubular casing, a cap thereon, a spirally-grooved spindle within the cap, a transverse pin from which the spindle is loosely hung, a hollow stem, a nut thereon engaging the spindle, and a spring for projecting said stem, 70 substantially as described.

In testimony whereof I have signed my name to this specification in the presence of two subscribing witnesses.

ZACHRY T. FURBISH.
